[57] CLAIM

The ornamental design of an infrared adapter for bidirectional infrared communication between a portable computer and a network computer, as shown and described.

DESCRIPTION

FIG. 1 is a perspective view of an infrared adapter for bidirectional infrared communication between a portable computer and a network showing my new design;

FIG. 2 is a front elevation view of the infrared adapter of FIG. 1;

FIG. 3 is a top plan view of the infrared adapter of FIG. 1; FIG. 4 is a side elevation view of the infrared adapter as seen from the right side of FIG. 2;

FIG. 5 is a side elevation view of the infrared adapter as seen from the left side of FIG. 2;

FIG. 6 is a back elevation view of the infrared adapter of FIG. 1; and,

FIG. 7 is a bottom plan view of the infrared adapter of FIG. 1.
